Primary Examiner — Thomas Johannes(74) *Attorney, Agent, or Firm* — Ogilvy Renault LLP(57) **CLAIM**

The ornamental design for a container, as shown and described.

DESCRIPTION

FIG. 1 is a perspective view of a container in a closed state, showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof; and

FIG. 8 is another perspective view thereof, in an open state; and,

FIG. 9 is a cross section view thereof taken in the direction of line 9-9 in FIG. 6.

The lightweight broken line portion of the figure drawings is included to show unclaimed subject matter only and forms no part of the claimed design. The heavy weight dashed line in FIG. 8 schematically shows claimed tear perforations.
